S. THOMASSEN.
EYEGLASSES.
APPLICATION FILED APR. 6, 1918.

1,283,600.

Patented Nov. 5, 1918.

Soren Thomassen Inventor

By his Attorney

Ivan E. A. Konigsberg

UNITED STATES PATENT OFFICE.

SOREN THOMASSEN, OF NEW YORK, N. Y.

EYEGLASSES.

1,283,600.

Specification of Letters Patent.

Patented Nov. 5, 1918.

Application filed April 6, 1918. Serial No. 226,972.

To all whom it may concern:

Be it known that I, SOREN THOMASSEN, a citizen of the United States, and resident of New York city, in the county of New York and State of New York, have invented certain new and useful Improvements in Eye-glasses, of which the following is a specification.

This invention relates to eyeglasses. The object of the invention is to provide means adapted to be interposed between the mounting brackets and the lenses so as to prevent breakage and permit the mounting to be screwed tight on to the lens. One object of the invention is to provide a lining or spacing member to coöperate with the mounting for the purpose set forth. Another object is to provide the lining or spacing member as an article of manufacture.

The invention will be more fully understood from the following specification read with reference to the accompanying drawing in which—

Figure 1 is a perspective view of a lining for eyeglasses embodying the invention;

Fig. 2 is a sectional view on a large scale of a portion of an eyeglass lens and the mounting; and

Fig. 3 is a view of a portion of an eyeglass. Referring to Figs. 2 and 3, the reference numeral 5 denotes the lens of an eyeglass and 6 the mounting. The latter is provided with a bracket portion 7 and two ears 8 and 9 between which parts a recess is formed to receive the lens 5 in the usual manner. The lens is secured to the bracket by a screw 10.

It is well known that the thickness of the lens is often less than the distance between the ears 8 and 9. Consequently the screw 10 must be screwed in very tight so as to bring the ears close to the lens and very often the lens breaks because of the pressure required. It is also well known that the screw often becomes loosened because it has not been screwed in tight enough for fear of breakage.

The object of the invention is to provide means to overcome these difficulties. As seen in Fig. 1, the lining member for the mounting consists of an element in the form of a clip comprising a back 12 and two apertured ears 13 and 14. The lining member may be

made of cardboard, paper, fiber, rubber, cel-luloid, or other similar or suitable material. The ears 13 and 14 are provided with apertures 15 and 16 slightly smaller, preferably, than the holes 17 and 18 in the ears 8 and 9.

When the lens is mounted the lining is laid within the mounting as shown in Fig. 2, the ears 13 and 14 corresponding to and fitting with the ears 8 and 9 and the several holes and apertures coinciding. The back 12 is laid against the bracket 7.

Thereafter the lens is placed in position and screw 10 screwed in. It will be seen that the lining takes up and fills the space between the lens and the mounting due to differences in size, and if the lens fits the mounting accurately, the use of the lining will cause the ears 8 and 9 to spring slightly apart. The screw may be screwed in very tightly because the lining will give under the pressure and prevent the lens from breaking. And because the holes in the lining are slightly smaller than the holes in the ears of the mountings, the edges thereof will be caught by the screw as indicated at 20 and as the screw thus will be more firmly seated because of the softer material of the lining, the screw will not work loose as easily as it so often does.

I have found the lining member to be very practicable, easy to use, it is practically invisible and materially assists in preventing breakage and loose screws in eyeglass mounting.

I claim—

1. The combination with the lens and the mounting of an eyeglass, said mounting consisting of an edge bracket and opposed apertured ears, of a lining member adapted to fit between said mounting and the lens and consisting of an edge member and opposed integral ear members adapted to coincide with the ears aforesaid and having apertures slightly smaller than the aperture of the said opposed apertured ears.

2. The combination with the lens and the mounting of an eyeglass, said mounting consisting of an edge bracket and opposed apertured ears, of a lining member adapted to fit between the said mounting and the lens and consisting of an edge member and opposed

integral ear members adapted to coincide with the ears aforesaid and having apertures coinciding with the apertures in said ears.

3. As a new article of manufacture a lining member for eyeglass mountings consisting of an edge member adapted to fit the edge of the lens and opposed apertured ear

members bent at an angle to said edge member.

Signed at New York, in the county of 10
New York and State of New York, this fifth
day of April, A. D. 1918.

SOREN THOMASSEN.
